UNITED STATES PATENT OFFICE.

TROY MORRIS, OF MOREHEAD CITY, NORTH CAROLINA.

OIL PAN FOR OIL STOVES.

Application filed November 5, 1926. Serial No. 146,436.

The invention relates to an improvement in fuel reservoirs for oil burners of cooking stoves or the like, and more especially to an oil control device for oil burners.

5 The primary object of the invention is the provision of a reservoir or control device of this character, wherein a uniform flow of oil to the flame or burner will be had, so that there will be no fluctuation in the flame, 10 as the oil from the main reservoir is discharged or delivered, the reservoir or control device being of novel form and simulates a pan or cup of special design to permit water within the oil to gravitate to a 15 low level relative to the oil, so that the water can be drawn off without disturbing the body of oil therein.

Another object of the invention is the provision of a reservoir or control device of this 20 character, wherein the oil from the main reservoir will be thoroughly strained, before the same is delivered to the burner or flame and such oil will be maintained at all times at a predetermined level and the pressure 25 of the oil against the flame be constant.

A further object of the invention is the provision of a reservoir or oil control of this character, wherein the oil content of the main reservoir can be completely utilized, 30 without liability of fluctuation in the flame and the pressure of the oil against the flame be constant at all times, the oil being strained and the water being present within the oil gravitated to the lowest point of the reservoir or control, so that it can be drawn off 35 at will without affecting the contents of said reservoir or control device.

A still further object of the invention is the provision of a reservoir or oil control device 40 of this character, which is extremely simple in construction, thoroughly reliable and efficient in its purpose, strong, durable, and inexpensive to manufacture and install.

With these and other objects in view, the 45 invention consists in the features of construction, combination and arrangement of parts, as will be hereinafter fully described in detail, illustrated in the accompanying drawing and pointed out in the claim hereunto appended.

In the accompanying drawing:

Figure 1 is a vertical longitudinal sectional view through the fuel reservoir or oil control device, showing fragmentarily the 50 main oil reservoir in position relative thereto.

Figure 2 is a horizontal transverse sectional view taken in the plane of the discharge outlet of said fuel reservoir or oil control device, the main reservoir being removed.

Similar reference characters indicate corresponding parts throughout the several views in the drawing.

Referring to the drawing, in detail, 5 designates a pan or cup shaped auxiliary fuel reservoir of an oil stove, having an elbow pipe 6 leading therefrom at a point elevated from the lowest point of said reservoir, the wall of the latter being formed with a perforated internally threaded bore or nipple 7 into which is tapped the pipe 6 which is extended through the frame 8 of the stove and leads to the burner, only a portion of the frame of the stove being shown and the burner thereof is omitted.

The body of the auxiliary fuel reservoir or oil control device 5 is formed with an opened upper flanged end 9 constituting a bearing rim for the main receptacle or oil reservoir 10, comprising the usual glass bottle, which is inverted over the auxiliary reservoir as is clearly shown in Figure 1 of the drawing. This bottle 10 has a valve cap 11 threaded on its neck and carrying a valve structure, as usual, provided with an unseating plunger 12 for the valve proper of the valve structure so that when the said valve is open the contents of the bottle 10 will readily flow into the auxiliary reservoir or oil control device.

The bottom 13 of the body 5 of the auxiliary reservoir or fuel control is upwardly struck to provide a crown 14 therein having a central reinforced nipple 15 in which is engaged a drain cock 16 of conventional type. Within the body 5 superposed relative to the crown bottom 14 is a conoidal shaped hood 17 of triangular contour and sectional plan and having at the three sides thereof supporting feet 18 which rest upon the bottom 13 concentrically of the crown 14, so that the accumulation of water from the oil within the body 5 which is gravitated to the bottom of said body, can be drawn off on opening the valved cock 16, as the water will flow from the body 5 in the direction of the arrow in Figure 1 of the drawing beneath the hood 17.

The apex 19 of the hood 17 will constitute an abutment for the plunger 12 of the valve structure in the cap 11 on the main reservoir 10 so as to unseat the valve of said valve

structure when the main reservoir is inverted and resting upon the rim 9 of the body 5, whereby oil will gravitate from the main reservoir 10 into the auxiliary reservoir or oil control device and reach a level therein as is shown in said Figure 1 of the drawing.

The body 5 is held stationary and supported by a bracket 20 fixed to the frame 8 of the oil stove.

The discharge port 7 of the body 5 has covering the same fine and coarse strainners 21 and 22, respectively, the same being held fast by solder or otherwise interiorly of the body 5 of the auxiliary reservoir or oil control device hereinbefore described. These strainners 21 and 22 will serve to strain the oil in the auxiliary reservoir or oil control device when being delivered to the burner of the oil stove or other like structure through the pipe 6 as will be clearly apparent.

It will also be apparent that when water accumulates in the bottom of the auxiliary reservoir or oil control device, with the oil above the same, such water can be drawn off from this reservoir or device by the opening of the cock 16, the water being caused to flow beneath the hood 17 in the manner as indicated by the arrow disclosed in Figure 1 of the drawing.

The legs 18 supporting the hood 17 are fastened to the bottom 14 of the pan body 5 in any suitable manner, preferably by solder, so that the hood will not become dis-

placed from its location in the body 5 of the auxiliary reservoir or oil control device. The supply pipe 6 is held fast on the frame 8 of the stove or like device by the cleat 23 which is suitably fastened to the said frame as illustrated in Figure 1 of the drawing.

From the foregoing it is thought that the construction and manner of operation of the device will be clearly apparent and therefore a more extended explanation has been omitted.

What is claimed is:--

A device for the purpose set forth comprising a cup shaped element providing an auxiliary reservoir and having a flanged upper end for receiving and supporting a supply receptacle in position to discharge into the reservoir, said element provided at its bottom, centrally thereof, with a crown shaped portion formed with an integral, depending outlet nipple, a conoidal-shaped hood positioned over and spaced from said crown shaped portion, said hood of triangular contour in sectional plan, spaced legs secured to the lower end of the hood and seated on the bottom of said element adjacent said crown shaped portion, a valve support for connection to the discharge point of the supply receptacle, and a valve unseating plunger acted upon by the apex of the hood.

In testimony whereof, I affix my signature hereto.

TROY MORRIS.
